UNITED STATES PATENT OFFICE

163,933

CUTLERY HANDLE OR THE LIKE

Lawrence K. Carroll, Fremont, Ohio, assignor to Quikut, Inc., Fremont, Ohio, a corporation of Ohio

Application April 18, 1949, Serial No. 2,108

Term of patent 14 years

(Cl. D44—29)

To all whom it may concern:

Be it known that I, Lawrence K. Carroll, a citizen of the United States of America, residing at Fremont, Sandusky County, Ohio, have invented new, original, and ornamental Design for a Cutlery Handle or the like, of which the following is a specification, reference being had to the accompanying drawings:

Fig. 1 is a view in side elevation of a cutlery handle or the like, showing my new design;

Fig. 2 is a view in side elevation looking from the left in Fig. 1; and

Fig. 3 is a view in section on the line III—III, Fig. 1.

I claim:

The ornamental design for a cutlery handle or the like, as shown.

LAWRENCE K. CARROLL.
